UNITED STATES PATENT OFFICE.

GEORGE W. KELLOGG, OF ROCHESTER, NEW YORK, ASSIGNOR TO KELLOGG MANUFACTURING COMPANY, OF ROCHESTER, NEW YORK, A CORPORATION OF NEW YORK.

TUBING FOR AIR-PUMPS.

1,284,359.

Specification of Letters Patent. Patented Nov. 12, 1918.

Application filed December 15, 1916. Serial No. 137,074.

To all whom it may concern:

Be it known that I, GEORGE W. KELLOGG, of the city of Rochester, county of Monroe, and State of New York, have invented certain new and useful Improvements in Tubings for Air-Pumps; and I hereby declare the following to be a full, clear, and exact description of the same, reference being had to the accompanying drawings, forming a part of this specification, and to the reference-numerals marked thereon.

My present invention has for its object to provide certain improvements in the construction of pumps, particularly air pumps intended to be used for inflating pneumatic tires, the novel features of which will appear more fully in the following specification, and will be pointed out particularly in the claims appended hereto.

20 In the drawings:

Figure 1 is a front elevation of the joint of the tubing for the cylinders of an air-pump constructed according to my invention, and

Fig. 2 is a cross section of the same.

25 Similar reference numerals throughout the drawings indicate similar parts.

The tubes 1 for an air-pump constructed in accordance with my invention may be made of any convenient or preferred length 30 or diameter and are closed at their ends by any suitable or convenient means. The cylinders are preferably constructed from flat sheet metal plates, which are rolled, or otherwise formed to cause the edges thereof to meet squarely, or abut each other, thus forming a butt joint as indicated at 2. Certain disadvantages exist in a joint of this character, owing to the difficulty which has been experienced in rendering the joint airtight throughout its length, and also providing the necessary strength or rigidity, as it has been found in practice that a tube having a joint of this character is weak along the joint, and when it is closed by soldering 40 the joint proper, it is also difficult to maintain the inner surface of the tube free from obstruction. In order to overcome these difficulties, I provide a reinforcing strip 3 on the exterior of the tube, formed of a strip 45 of metal which may be thinner or of lighter gage than the sheet from which the tube is formed. The edges of this strip are folded over as indicated at 4, the bending occurring

in a direction away from the body of the tube. This doubling or folding over of the 55 metal accomplishes a further result, which is more important than that of merely strengthening the strip, in that it provides a smooth curved surface lying in close engagement with the curved wall of the cylinder 60 and forming a longitudinal V-shaped depression 5 for the reception of the solder. The formation of a joint strip in the form described is particularly advantageous because tin plate, which is inexpensive, may 65 be used, as the bending of the edges provides a smooth continuous edge coated with tin, which possesses an affinity for the solder. The formation of a joint of this character, in which the edges of the plate are first butted 70 together and then secured by a longitudinally extending exterior strip, may also be employed in making the pump cylinders of tin plate, the required interior smoothness of the tubes being assured, and the maximum 75 strength obtained at a minimum cost.

An air-pump embodying my invention possesses the advantages of durability and serviceability united with cheapness in the cost of manufacture.

80 I claim as my invention:

1. An article of manufacture comprising a cylindrical tube formed by bending a metal sheet to abut the edges thereof to form a longitudinally extending joint and a strengthening strip overlying the joint formed with bent over edges and solder applied between said edges of the strip and tube at opposite sides of the joint.

85 2. An article of manufacture a tube composed of sheet metal bent into cylindrical form to cause the edges of the sheet to form a butt joint and a strip applied over the joint having its edges bent over in a direction outwardly from the tube and soldered thereto.

90 3. An article of manufacture composed of a tube formed by bending into cylindrical form a sheet of tin-plate and a binder applied over the adjacent edges of the latter formed of a strip of tin-plate having its 100 edges bent over in a direction outwardly from the tube and solder applied at the edges of the strip and adhering to the tin surfacing of the binder and tube.

GEORGE W. KELLOGG.

Copies of this patent may be obtained for five cents each, by addressing the "Commissioner of Patents, Washington, D. C."
